DOG TOY

LaVerne Frifogle, 61 N. Turner Road,
Youngstown, Ohio 44515

Filed July 6, 1970, Ser. No. 23,831

Term of patent 14 years

Int. Cl. D30—99

U.S. Cl. D30—42

FIG. 1 is a front elevation of a dog toy showing my new design;

FIG. 2 is a side elevation thereof;

FIG. 3 is a top plan view thereof.

The back is a substantial duplicate of the front.

I claim:

The ornamental design for a dog toy, as shown and described.
